CLAIM

The ornamental design for a remote control for electric bed, as shown and described.

DESCRIPTION

FIG. 1 is a perspective view of a remote control for electric bed, showing the new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken lines depict portions of the remote control for electric bed and form no part of the claimed design.

1 Claim, 6 Drawing Sheets
